METHOD AND MEANS FOR AIDING THE BLIND

Joseph D. Shaw, Cincinnati, Ohio

Application June 9, 1953, Serial No. 360,438

5 Claims. (Cl. 340—213)

The present invention relates to a system for aiding the blind, embodied in a portable unit and comprised essentially of a means for electrically stimulating a blind person's visual cerebral area through the operation of a light responsive means positioned for energization by the person's circumambient illumination.

It is an important object of this invention to provide a novel visual aid system for a blind person which will create for that person a perceptible image patterned after the general illumination and the intensity of light reflected from objects surrounding said blind person.

Another object of this invention is to provide a light operated relay system adapted to transmit separate signals indicative of the intensity of light at given points in the area immediately surrounding the blind person and to electrically stimulate the parts of the visual cerebral areas of the person which substantially correspond to the given points.

Heretofore aids to the blind did not produce a sensation of light in the blind persons but relied upon giving them either an auditory or a tactile sensation as a signal that an object was in the immediate vicinity. In my system a photo-electric tube controls the intensity and/or the frequency of an electric stimulus which is applied either directly by internal electrodes, or indirectly by external electrodes or an induction coil to the brain in the vision areas of a blind person. For the successful use of my system the vision area of the blind person's brain must not have atrophied and care should be taken during utilization of my system that the electrical stimulus produced thereby does not reach an intensity that would damage the said brain area.

Further objects and advantages of this invention will be brought out and become apparent in the following specification, reference being had to the accompanying drawing, in which:

Fig. 1 is a schematic wiring diagram of one form of the system for aiding the blind in accordance with my invention.

Fig. 2 is a wiring diagram of a modified form of my invention.

Fig. 3 illustrates diagrammatically another means for applying my system to the person of the blind.

Fig. 4 illustrates still another way of applying my system to a blind person.

Referring now to Fig. 1 the drawing VT₁ is a photoelectric cell or phototube having a cathode 1 which emits electrons when exposed to light and an anode 2 which attracts electrodes because the latter is operated at a positive potential. In this type of tube the number of electrons emitted by the said cathode and hence the voltage across the tube are proportioned to the amount of light falling on its sensitized surface. The phototube is positioned on the front of the person of the blind either by securing its socket piece directly to the clothing or mounting the socket upon a frame that may be readily secured to a part of the person. The circuit wire extensions for the phototube are indicated by the numerals

2

3 and 4 which connect the phototube to a trigger circuit 5 whose parts may be mounted in a case carried about the blind person's body or clothing. The trigger circuit is adapted to convert the voltage change in the phototube to electrical stimulating impulses that can be applied to the visual area of a blind person's brain through electrodes connected to the output of the trigger circuit. This trigger circuit comprises a battery EB₁ having one side connected to the anode lead 4 of the phototube and to a resistance R₁ by a line 7, whilst the other side of said battery is connected to condensers C₁ and C₂ by a line 8. Condenser C₁ is also connected to the cathode lead 3 of the phototube while condenser C₂ is connected by a line 9 to the resistance R₁. The grid 10 of a gas triode tube VT₂ is connected to line 3 while its plate 11 is connected to the primary of a transformer T₁, the opposed end of the transformer being connected to line 9 between its connections to the condenser C₂ and the resistance R₁. The secondary leads of the transformer are connected across a potentiometer P₁ which in turn has each of its extended leads 12 and 13 electrically connected to a pair of conductors such as electrodes 14 and 15, respectively, applied either exteriorly or interiorly to the brain 16 in stimulating positions with respect to the vision area 17 of a blind person 18.

In the operation of my system the phototube is positioned upon the front of a blind person preferably on a portion of his body subjacent the head while the case enclosing the trigger circuit 5 may be attached to the clothing, mounted upon a belt, or suspended from the shoulders of the person in a suitable position on the back. The electrodes may terminate in a suitable plastic socket applied by surgery in and through the skull of the blind person, suitable electrical connections and flexible circuit wires connecting the parts together in any number of ways that will readily suggest themselves to those conversant with the art.

Circumambient light impinging on the phototube VT₁ allows the condenser C₁ to be charged by battery EB₁. The more light impinging on the phototube the faster the condenser C₁ is charged. When the condenser C₁ has been charged to a value such that the voltage across it is equal to the ignition potential of the gas triode tube VT₂, said tube ignites and the condenser C₂, which has been charged through resistance R₁, now is discharged through the primary of the transformer T₁ and the gas triode VT₂. The more light impinging on the phototube VT₁ the more rapidly the condenser C₁ is charged to the ignition potential of the gas triode VT₂. Accordingly the more rapidly the condenser C₁ is charged to the ignition potential of the gas triode VT₂, the more frequently the condenser C₂ is discharged through the primary of the transformer T₁. The discharge of the condenser C₂ through the primary of the transformer T₁ produces a voltage across the secondary of the transformer T₁ which voltage is applied across the potentiometer P₁. The output of the potentiometer P₁ is connected to the electrodes which are applied to the brain in the vision areas. When the brain is stimulated the person receives a sensation of light. Therefore the more intense the light the more frequently the brain is stimulated with a resulting sensation of light. If there is no light, no sensation of light will be produced.

It is also contemplated that the frequency of the brain stimulus may have a constant value whilst variations in the intensity of the circumambient light impinging on the phototube will proportionately vary the intensity of said brain stimulus. Fig. 2 illustrates a system for accomplishing this objective wherein it will be noted that the phototube VT₁ of the system shown in Fig. 1 is replaced by a resistance R₂. A condenser C₃ will therefore charge at a rate independent of the light intensity but

dependent on the resistance R_2 . Accordingly the frequency of discharge of the condenser C_3 and therefore of the stimulator is independent of the light intensity. However, the secondary of the transformer T_2 is applied in series with a circuit consisting of the potentiometer P_2 and a triode tube VT_3 . The grid 19 of the triode VT_3 is connected to its cathode 20 through the grid bias battery E_{CC} and the resistance R_3 . A phototube VT_4 is connected in series with the resistance R_3 and a source of plate voltage EB_2 . When light impinges on the phototube VT_4 , more current exists in the phototube VT_4 ; and accordingly more current exists in the resistance R_3 . With more current in the resistance R_3 , there is a greater voltage across said resistance R_3 . When the phototube VT_4 and the plate voltage EB_2 are connected as in Fig. 3, the voltage across the resistance R_3 tends to make the grid 19 less negative with respect to its cathode 20. Accordingly the triode VT_3 is able to conduct more readily and now acts as a low resistance in series with the potentiometer P_2 . Therefore the voltage to the electrodes will be increased. Accordingly as more light impinges on the phototube, the more intense is the stimulus. This stimulus is applied through the electrodes to the brain as described in reference to Fig. 1. Accordingly the more intense the light the more intense the stimulus and the more intense the sensation of light.

An important variant of my invention is depicted diagrammatically in Fig. 3 of the drawing which shows a number of electrodes 20 applied to the brain 21 of a blind person such that each is located in a different part of the vision area to form a kind of electrode pattern. Each electrode is connected to a circuit 50 which has either the constant frequency output of Fig. 2, and/or the variable frequency output of Fig. 1. Each of the circuits 50 has an individual phototube 22 and the phototubes are preferably mounted within a box 23 worn on the front of the person of the blind. The box is similar to a camera obscura in that it is interiorly darkened and has a lens 24 positioned in an opening in its front wall which transmits images of external objects toward a back wall 25. This back wall carries the phototubes 22, which are mounted thereon in a pattern corresponding to the pattern of the electrodes 20 as applied to the brain. As indicated in Fig. 3 an output lead of each circuit 50 could be connected to an indifferent part of the blind person's body thus providing a common electrode for each circuit 50 and requiring that but a single electrode be applied to the vision area of the brain to produce the required stimulus therefor. It will therefore be understood that circumambient light will impinge with varying intensities on each of the phototubes in the pattern and each will in turn vary the intensity of the stimulus imparted by its particular electrode to the part of the vision area in which it is located thus producing a light and shadow pattern of sensation in the blind person's brain, who may with practice learn to translate the pattern into a meaning indicative of the general illumination and the positions of physical objects in his immediate surroundings.

The output of the stimulating circuits shown in Figs. 1 or 2, or a combination of both, would also be applied to the brain by an inductance coil 26 secured as shown in Fig. 4 to the exterior of the blind person's head by a band 27, or the like.

It will be seen from the above that I have provided a novel system for aiding the blind in that the blind will actually have a sensation of light whose intensity and pattern may be related by him to the physical objects immediately surrounding him. Further the electrical apparatus is relatively simple and can be compactly enclosed in a suitable light weight case for easy portability. It has been demonstrated that electrodes may be applied to the brain by an operation and that when in place they cause the person no discomfort because there are no pain receptors in the brain.

Having described my invention in as clear and exact language as it is now possible for me to use, what is claimed is:

- 15 1. A system for aiding the blind comprising an electric conductor in stimulating position with respect to the vision area of a blind person's brain, a phototube exposed to the circumambient light of the blind person, and a circuit connected to the phototube and adapted to translate the change in magnitude of the current produced by the phototube into a variable sensitizing output current, and means connecting the conductor to the circuit output to thereby produce variable stimuli within the vision area of the blind person's brain.
- 20 2. A system for aiding the blind comprising a plurality of spaced electric conductors arranged in a pattern in stimulating positions with respect to the vision area of the brain of a blind person, a number of phototubes arranged on the blind person in a pattern corresponding to the conductor arrangement, a circuit connected to each of the phototubes and adapted to translate the change in magnitude of the current produced by its phototube into a proportionally variable, sensitizing output current, and means for connecting each conductor with its respective circuit output to thereby simultaneously produce variable, localized stimuli in the vision area of the blind person's brain.
- 25 3. A method for aiding the blind comprising subjecting a light responsive means to the circumambient light of the blind person, causing a change to occur in the light responsive means in response to a change of intensity of the circumambient light, translating the change into stimuli whose values are altered proportionately by the change in the light responsive means, and subjecting the visual area of the blind person's brain to the effect of the stimuli.
- 30 4. A method for aiding the blind as set forth in claim 3 characterized by the fact that the intensity of the stimuli is proportionally altered by the change in the light responsive means.
- 35 5. A method for aiding the blind as set forth in claim 3 characterized by the fact that the frequency of the stimuli is proportionally altered by the change in the light responsive means.
